(57) CLAIM

The ornamental design for a wall phone, as shown and described.

DESCRIPTION

FIG. 1 is a perspective view of a wall phone according to the invention.

FIG. 2 is a front elevational view of a wall phone according to the invention.

FIG. 3 is a front elevational view of a wall phone according to the invention, shown with handset displaced from the cradle.

FIG. 4 is a rear elevational view of a wall phone according to the invention.

FIG. 5 is a left side elevational view of a wall phone according to the invention.

FIG. 6 is a right side elevational view of a wall phone according to the invention.

FIG. 7 is a top plan view of a wall phone according to the invention; and,

FIG. 8 is a bottom plan view of a wall phone according to the invention.

The broken line showing of the various parts and features is for illustrative and contextual purposes only and forms no part of the invention.
